UNITED STATES PATENT OFFICE.

JACKSON ROSS HAZELRIGG, OF EXETER, CALIFORNIA.

WALL CONSTRUCTION.

Application filed December 27, 1923. Serial No. 682,947.

My invention is an improved wall construction.

The object of my invention is to provide a double concrete wall with expansion joints to prevent cracking.

A further object is to provide a wall which may be quickly and inexpensively erected.

In the annexed drawings in which my invention is illustrated:

Figure 1 is a fragmentary side view of my completed wall.

Figure 2 is a fragmentary plan view of the same showing an expansion joint.

Figure 3 is a fragmentary side view of my wall showing an expansion joint.

Figure 4 is a sectional view taken on the line 4—4 of Fig. 2.

Referring more particularly to the drawing, my construction includes primarily an outer concrete wall 1, an inner concrete wall 2, and reinforcing columns or studding 3, positioned between said walls. These columns each consist of two timbers 4 and 5 placed face to face and secured together with a coil of reinforcing wire 6 placed therebetween, which wire projects beyond the edges of the timbers and is embedded in the concrete wall's 1 and 2, thus binding the walls together and reinforcing them.

To prevent cracking of the walls due to the expansion and contraction thereof expansion joints 7 are provided. These consist of two vertical channels 8 and 9 secured

transversely in the wall, and with the channel 9 fitting within the channel 8. A column 3 is positioned back of each of the channels 8 and 9 to further strengthen the wall at this point. As the wall expands and contracts horizontally the channel 9 will slide within the channel 8.

My wall is preferably erected in two sections, the first extending to a plane at the lower edge of the windows, and the second to the roof plane as shown in Fig. 1.

Having described my invention, I claim:

1. A wall construction comprising a wall formed of a plurality of sections, each section having an inner concrete wall and an outer concrete wall spaced therefrom, a reinforcing column between said inner and outer walls, and a vertical channel on each section having slidable engagement with a complementary vertical channel on another section to form an expansion joint therebetween. 55

2. A wall construction comprising a wall formed of a plurality of sections, each section having an inner concrete wall and an outer concrete wall spaced therefrom, a reinforcing column between said inner and outer walls and a vertical channel secured transversely in each section having slidable engagement with a similarly arranged complementary vertical channel on another section to form an expansion joint therebetween. 65

In testimony whereof I affix my signature.

JACKSON ROSS HAZELRIGG.
